ABSTRACT OF THE DISCLOSURE

Undesired TE type modes in re-entrant cavity resonators of high frequency electron discharge devices which include klystron and coupled cavity slow-wave circuits incorporating re-entrant drift tube sections can be suppressed to a great extent by a combination of lossy loading material deposited on the surfaces of axially slotted drift tubes in the region of the slots. The axial slots provide a dual function of reducing the resonant frequency of TE type modes in re-entrant cavities thus permitting the tube designer to eliminate any correspondence between the resonant frequency of undesired TE type cavity modes and second harmonics of the operating mode by tuning the mode either above or below the 2nd harmonic as well as increasing the current path lengths of the undesired TE type modes to permit easy reduction of the unloaded Q (Q_0) of the mode without substantial perturbation of operating mode of the cavity and device. The utilization of lossy R.F. attenuating means in the slotted regions provides excellent stabilization by further reduction to Q_0 for the undesired modes.

In United States patent application Ser. No. 342,217 by Albert D. La Rue et al., filed Feb. 3, 1964, and assigned to the same assignee as the present invention a rather thorough discussion of the nature of cavity oscillations and a novel solution for suppression of same is given which involves the utilization of distributed loss techniques.

BRIEF SUMMARY OF THE INVENTION

This invention relates in general to the field of high frequency electron discharge devices operable in the microwave spectrum and more particularly to improved mode suppression means for undesired modes in re-entrant cavity resonator portions of such devices.

The excitation of undesired cavity modes in a high frequency electron discharge device is deleterious to the device operating efficiency as well as to the quality of the output signal and can produce undesired spurious signals as well. As operating powers increase beam currents increase and the chances of reaching the start oscillation current value for any given undesired cavity mode increase accordingly. This invention is concerned with providing a novel mode suppression approach for high frequency electron discharge devices incorporating re-entrant cavity resonators which has been found to be particularly useful in reducing the Q_0 for TE types of modes and particularly for the TE_{111} type of mode. The invention in its basic form involves the introduction of a plurality of elongated slots in the re-entrant drift tube portions which has been determined to provide increased current path lengths for the TE_{111} type of mode without substantially perturbing the operating mode. The length of the slots which form a plurality of fingers can be used to control the resonant frequency of the undesired mode to a considerable degree as well as the reduction in Q_0 for the undesired mode and by incorporating lossy R.F.

2

attenuating material on the drift tube slotted surfaces an additional significant reduction in Q_0 for the undesired mode is achieved. Good results have been obtained by using lossy material on the inside, the outside and both inside and outside of the re-entrant drift tubes in conjunction with radial and nonradial slots as well as with in-phase and out-of-phase slots.

It is therefore an object of the present invention to provide improved mode suppression means for high frequency electron discharge devices operable in the microwave spectrum and incorporating re-entrant cavity resonators.

A feature of the present invention is the provision of a high frequency electron discharge device incorporating cavity resonators with re-entrant drift tubes with a plurality of slots in the re-entrant drift tubes.

Another feature of the present invention is the provision of a high frequency electron discharge device incorporating cavity resonators with re-entrant drift tubes with a plurality of slots in the re-entrant drift tubes in conjunction with lossy R.F. attenuating material in the slotted regions.

These and other features and advantages of the present invention will become more apparent upon a perusal of the following specification taken in conjunction with the accompanying drawings wherein:

FIG. 1 is a schematic representation of a high frequency electron discharge device incorporating the teachings of the present invention,

FIGS. 2A and 2B are enlarged transverse and longitudinal cross sectional views of the structure of FIG. 1 with the transverse view taken along lines 2—2 of FIG. 1 in the direction of the arrows,

FIGS. 2C—2H are views similar to that of FIG. 2A depicting alternative embodiments of the present invention,

FIG. 3 is a cut-away view of a re-entrant cavity resonator incorporating an out-of-phase slotted embodiment of the present invention,

FIGS. 4 and 5 are enlarged cross-sectional views taken along the lines 4—4 and 5—5, respectively of the embodiment depicted in FIG. 3,

FIG. 6 is a graphical plot of the variation of f_0 for TE_{111} type of modes with slot depth for various slot arrangements,

FIG. 7 is an illustrative graphical portrayal of the relationship between a typical fundamental and second harmonic frequency spread for S-band,

FIG. 8 is a transverse sectional view of a cavity resonator with re-entrant drift tubes depicting the field configuration for the operating TM_{010} type mode,

FIGS. 9A and 9B are longitudinal cross-sectional top and side views of a cavity resonator with re-entrant drift tubes showing the field configuration for a TE_{111} type mode,

FIG. 10 is a transverse sectional view of the re-entrant cavity resonator of FIG. 9A showing TE_{111} mode pattern as a complete transverse section through the cavity midplane in the area bounded by the drift tubes,

FIG. 11 is a transverse sectional view of a re-entrant cavity resonator depicting a pair of orthogonal TE_{111} modes in the area bounded by the drift tubes,

FIG. 12 is an illustrative graphical portrayal of the effects of slotted drift tubes on Q_0 for a TE_{111} mode both with and without loading in the slotted regions.

Turning now to FIG. 1 there is depicted a high frequency electron discharge device 10 which includes electron beam forming and projecting means 11 disposed at the upstream end portion of the device, electron beam collector means 12 disposed at the downstream end portion of the device and a plurality of re-entrant cavity

resonators 13 disposed along the beam path therebetween.

The electron beam forming and projecting means 11 can be of any conventional design such as, for example, a Pierce type gun having cathode emission surface 14, focusing anode 15 and main accelerating anode 16. A thermionic heater 17 can be used to induce thermionic emission from the cathode. Any conventional R.F. coupling means such as coaxial coupler 18 can be used to introduce R.F. energy into the input cavity and any suitable R.F. coupling means such as, e.g., waveguide 19 can be coupled to the output cavity or in a hybrid tube type the downstream portion of the slow wave interaction section to extract amplified R.F. energy.

Since the theory and operation of both the multicavity klystron amplifier of types such as depicted for example in U.S. Patent No. 3,169,206, by R. B. Nelson, issued Feb. 9, 1965, and assigned to the same assignee as the present invention, and hybrid devices which incorporate klystron buncher sections and traveling wave output sections such as, for example, shown in U.S. Patent No. 3,289,032 issued Nov. 29, 1966, by R. R. Rubert et al. and assigned to the same assignee as the present invention are well known, further elucidation on the general properties of these devices will not be given herein.

The Q_o reduction and frequency shifting teachings of the present invention are applicable to standard klystron type cavity resonators having re-entrant drift tubes such as illustrated in FIG. 1 or in hybrid tubes as discussed above as well as to slow-wave circuit traveling wave tubes incorporating coupled cavities having re-entrant drift tubes. The slow-wave coupled cavity circuits will differ from the klystron cavity circuits by the presence of additional coupling slots or regions between cavities which provide the circuit with a passband characteristic, (see for example, FIG. 5 of U.S. Patent No. 2,636,948) such that traveling wave tube operation is possible. These traveling wave tube coupled cavity resonators with re-entrant drift tube regions can support undesired TE type modes also and the teachings of the present invention are applicable thereto although specifically illustrated and exemplified with respect to the klystron. Therefore the terminology cavity resonators having re-entrant drift tubes as used hereinafter in the specification and claims shall be applicable to those coupled cavity slow-wave circuits which also utilize re-entrant drift tubes.

The high frequency electron discharge device depicted in FIG. 1 is representative of both the straight klystron type and the hybrid types which incorporate cavity resonators having re-entrant drift tubes 20.

In order to better understand the contribution of the present invention the following general discussion regarding the importance of relative Q 's for cavity resonators is given.

One may take the total effective cavity Q for any mode as:

$$\frac{1}{Q_t} = \frac{1}{Q_b} + \frac{1}{Q_o} + \frac{1}{Q_e}$$

Q_t is the total effective cavity Q

Q_b is the Q resulting from beam loading alone

Q_o is the normal unloaded cavity Q

Q_e is the Q resulting from any external load alone.

It is plain that Q_t will be reduced by any reduction of Q_o or Q_e . Thus an external load reducing Q_e or the use of lossy material reducing Q_o results in a reduction of Q_t . Q_b the beam loaded Q , may be negative or positive, depending on the gap conductance for the mode in question. If $1/Q_b$ is negative and larger in magnitude than $1/Q_o + 1/Q_e$, Q_t is negative, and oscillation is possible. One must therefore arrange conditions so that the sum of the positive terms on the right is larger in magnitude than the negative term $1/Q_b$ (if it should be negative).

In the present case we are concerned with how to effectively reduce Q_o for TE type modes such that Q_t will remain positive for these general types of modes. Experi-

mental analysis of a multicavity klystron amplifier operable in the S-band region of the microwave spectrum at a perveance of 3×10^{-6} in an attempt to design improved high power klystrons resulted in oscillations between 8100 mh. and 8175 mh. starting at 30 amps peak current. Extensive experimental analysis finally led to the conclusion that a TE_{111} type of mode was responsible for the oscillations. Further analysis of this type of mode led to the finding that mode was characterized in a re-entrant cavity resonator by strong transverse E fields in the vicinity of the interaction gap and internally of the drift tubes and had substantial axial E field components at the edges of the drift tubes.

The application of simple lossy R.F. coating on the exterior of the drift tubes as taught in copending U.S. Patent application Ser. No. 342,217 is not the optimum solution for Q_o reduction for this mode.

It was discovered that by introducing a plurality of elongated slots which produce a plurality of substantially axially directed and circumferentially spaced current flow paths in the re-entrant portions of the drift tubes such as to form a plurality of fingers that it was possible to both reduce Q_o for TE type modes and to tune the mode down in frequency which not only provided increased current flow paths but enables the tube designer to shift the resonant frequency of the mode sufficiently to preclude any correspondence between the f_o of the mode and second harmonics of the fundamental in the operating band of the tube which can be quite wide for heavily loaded cavities and especially so if broad band techniques and tunable cavities are provided. In other words, the mode can be tuned above or below the 2nd harmonic as desired.

A particularly desirable feature of the use of elongated slots in re-entrant drift tubes is the fact that very little effect on the fundamental mode occurs. For example, an S-band cavity with a gap of 0.582 inch and a symmetrical pair of drift tubes each having a re-entrant length of .435 inch was analyzed and found to support a TE_{111} mode at around 8100 to 8175 mh. The drift tubes were then slotted with 16 radial slots cut in each drift tube to a depth of .375 inch each. This produced a shift in the f_o of the TE_{111} mode down to around 6000 mh. and a shift of only around 6 mh. for the fundamental TM_{010} type mode. Similar results were obtained with diverse types of slotting arrangements which shows the excellent mode selectivity of the slotted drift tube technique. By combining the slotted re-entrant drift tube approach with lossy R.F. attenuating coatings on the drift tubes substantial reductions in Q_o for the TE_{111} type of mode were obtained. Good results were obtained with various types of slotting approaches and attenuating coatings. For example, Q_o reductions of better than 5 to 1 were obtained by using various combinations of slots and internal, external and both internal and external lossy R.F. coatings on the re-entrant portions of the drift tubes as will be shown in more detail in the accompanying tables set forth hereinafter.

As discussed previously, if positive stability for any given undesired mode is wanted, it is merely necessary to design the cavity such that

$$\frac{1}{Q_t} = \frac{1}{Q_b} + \frac{1}{Q_o} + \frac{1}{Q_e}$$

is positive for a particular mode.

If $1/Q_b$ is negative and Q_b is smaller than

$$\frac{1}{\frac{1}{Q_o} + \frac{1}{Q_e}}$$

then oscillations can occur. Thus, if one neglects Q_e entirely it is possible to assure stability by simply making Q_o for a given undesired mode smaller than Q_b for that mode. Any Q_e will obviously increase the stability safety factor. By combining the slotted drift tube approach with

lossy R.F. attenuating material it is very easy to do this since slotting by itself may not provide sufficient reduction in Q_o for the mode. At any rate the present invention is not restricted to any particular degree of reduction in Q_o for undesired modes since it is clearly a matter of individual design as to what values of Q_o , Q_e , and Q_b for a given mode under a given set of operating conditions are desired.

Turning now to FIG. 2A an embodiment of the slotted drift tube concept is depicted which utilizes 16 radial slots 21 in conjunction with lossy R.F. attenuating material 22 on the external portion of the drift tube 20 as shown. Good results were obtained with a Kanthal A applied by standard flame spraying techniques. Kanthal A is an alloy of 5% aluminum, 22% chromium, 0.5% cobalt and the balance iron. Naturally the thicker the coating (up to the skin depth for the particular frequency spectrum concerned) the better the Q_o reduction for the undesired mode.

Another embodiment of the present invention is depicted in FIG. 2B wherein 16 radial slots are shown in combination with lossy R.F. attenuating coating 22 on the exterior of the drift tube and 23 on the interior of the drift tube. Good results were obtained with flash plated iron deposited from an electrolytic bath in a well known manner to any desired thickness. The lossy R.F. attenuating material can obviously be of any commercially available type that is capable of handling the power levels involved and is not restricted to the above types. In both the embodiments of FIGS. 2A and 2B the slots were cut in opposing drift tubes in-phase or axially aligned.

In FIG. 2C a variation using parallel pairs of nonradial slots is depicted which combined 4 nonradial slots 24 with lossy R.F. attenuating material 25 on the external surface. This variation also produced good results.

In FIG. 2D a variation using nonradial and nonparallel slots 26 in conjunction with lossy R.F. attenuating material 27 is depicted. This approach also produced good results.

In FIGS. 3, 4 and 5 an out-of-phase slotted approach is depicted which was also found to be effective. It combines two pair of parallel nonradial slots 28, 29 in each drift tube which are 90° azimuthally space rotated in opposing drift tube sections in conjunction with lossy R.F. attenuating material 30 of the type set forth previously.

In each case if it is desired to minimize the chances of any of the lossy coating from breaking away from the slotted regions it may be removed from the slots or suitable masking may be employed so that only the exterior or interior or both surfaces are coated.

If it is desired to minimize loading of the fundamental mode in certain cavities such as, for example, the output cavity the lossy coating is deposited on the inside or exterior of the drift tube only or on the inside and only partially on the outside exterior of the drift tubes. For example, it can be removed from the gap ends.

Now it has also been determined experimentally that the introduction of any asymmetries in the cavities such as asymmetries in the slots or uneven distribution of lossy R.F. attenuating material can produce mode splitting of the TE_{111} type of mode which results in two orthogonal field patterns. This mode splitting will result in a distinct spaced pair of resonant frequencies such as denoted by A, C in FIG. 7. See FIG. 11 for a simplified pictorial representation of the E and H field patterns for this split mode.

Now the resonant frequency of the mode least effected by the slots may have risen from the unsplit value, B in FIG. 7, to A in FIG. 7. This means you will not have to tune a nonsplit TE_{111} mode down as far as a split mode to get out of the 2nd harmonic region, if the desired Q_o reduction requires that the mode be tuned down into or below the 2nd harmonic. It is preferable not to have the mode in the second harmonic frequency band, since second harmonic power may then be coupled into the mode and cause cavity heating and/or beam deflection by the transverse fields as well as increased instability. The use of a pair of in-phase nonradial slots such as shown in FIG. 2C has been found to produce a definite TE_{111} mode split into an orthogonal pair. This mode splitting can be alleviated however, if desired, by using the out-of-phase nonradial approach of FIGS. 3-5. This will effectively equally tune each of the orthogonal branches and produce a nonsplit TE_{111} type mode with a simple f_o as at B in FIG. 7. In any case, greater design freedom is obtained by preventing mode splitting.

Various combinations of slotting and loading techniques were investigated with the following results:

TABLE I.—SUMMARY OF EXPERIMENTAL RESULTS FOR TE_{111} MODE LOADING

Cavity	No.	Slots		Drift-Tube Lossy Coating	TE_{111} Mode		
		Depth, in.	Rad/Nonrad		f_o , Mh.	Q_o	$\Delta f/f_o$ **
4	0	0	—	None (but walls are kanthalized)	8,165	1,360	2.34
4	4	.350	In phase, nonradial	Rough kanthal on cylindrical part of outside.	7,210	144	2.17

* $\Delta f/f_o$ is proportional to mode impedance, measured with a .125 inch quartz rod on the axis giving a frequency shift of Δf , Mh. with a resonant frequency of f_o in Gh.

Of all the above solutions the 16 radial and in-phase combination was found to be preferred from an overall standpoint although each combination set forth above has obvious merits as a means for achieving substantial reduction of Q_o in TE_{111} type modes in re-entrant cavity resonators.

A complete klystron was designed with the Q_o reduction technique used with the following results when using the preferred in-phase, 16 radial slot approach:

TABLE II.—MEASUREMENTS OF TE_{111} MODE IN DRIVER CAVITIES OF MODIFIED KLYSTRON

Cavity	1	2	3	4	5	6
Orthogonal TE_{111} Modes:						
f_{111}	5,783	5,956	(*)	(*)	5,990	7,145
Q_{111}	126	108	(*)	(*)	120	140
f_{122}	6,042	6,028	6,026	6,046	6,021	(*)
Q_{122}	189	147	89	141	123	(*)
Gap, in.	.499	.583	.583	.582	.582	.342
Number of slots	16	16	16	16	16	16
Slot width, in.	$\frac{1}{32}$	$\frac{1}{32}$	$\frac{1}{32}$	$\frac{1}{32}$	$\frac{1}{32}$	$\frac{1}{32}$
Slot length, in.	.401	.360	.360	.360	.360	.292
Drift-tube lossy coating.	Very rough kanthal		0.0001 in. to 0.0005 in. iron plating.			
Location of lossy coating of drift-tubes.	Cylindrical part of O.D.		O.D. except .030 in. from tip, on I.D. from .30 in. to .430 in. from tip.			
Location of kanthal on cavity walls.	End walls and side wall		End walls only.			

*Not measured.

The effects on the f_o of the TE_{111} type mode of the number and kind of slotting technique used and on the depth of the slots is presented in FIG. 6 for a typical re-entrant cavity resonator having a pair of .435 inch re-entrant drift tubes using $\frac{1}{32}$ inch wide slots.

Curve A, B, and C are for 4 nonradial slots in each drift tube using two pairs of parallel slots spaced .625 inch apart as shown in FIGS. 2 and 3-5. Curves A and C represent the orthogonal pair for the in-phase case depicted in FIG. 2 and curve B represents the 90° spaced rotated approach of FIGS. 3-5 which shows that mode splitting is obviated by this technique.

Curve D is for the 8 nonradial slot case such as depicted in FIG. 2D.

Curve E is for the 8 radial slot case using equal spacing between slots which is not separately illustrated but which can be depicted in FIG. 2A, for example, by simply eliminating every other slot.

Curve F is for the 16 radial slot case such as shown in FIGS. 2A, 2B using even spacing between slots.

It is seen that the greater the number of slots the greater the corresponding reduction in f_o for TE_{111} type modes and that the greater the depth of the slots the greater the reduction in f_o for the TE_{111} type modes.

These results can be generalized by referring to FIGS. 8 and 9. In FIG. 8 a typical TM_{010} type of fundamental mode for re-entrant cavity resonators is depicted. In FIG. 9A and 9B a cross section of a re-entrant cavity resonator shows the TE_{111} type of mode which has a full wave pattern around the circumference with maximum transverse fields at the gap and also an appreciable axial component at the edges of the gap. Standard perturbation techniques can be used to identify this type of mode which in a pure cylindrical cavity would occur at a much lower frequency. FIG. 10 shows a transverse section of this mode pattern taken along the midplane of the cavity and in the area bounded by the drift tubes.

The utilization of the slotted drift tube with lossy material in the region of the slots as discussed above will effectively reduce the Q_o for any mode which has strong gap fields coupled with appreciable circumferential current flow paths on the drift tubes and in general this means TE mode types in contradistinction to TM mode types. The number of slots can obviously be varied from even the uneven numbers as well as spacing between slots without departing from the scope of the present invention. In

FIG. 12 the effects of variation in Q_o for the TE_{111} mode as a function of slot depth both with and without R.F. loading on the drift tubes is depicted for purposes of illustrating the rather startling reduction of Q_o for TE_{111} modes which occurs for simple slotting even without the use of lossy R.F. attenuating material in the slotted regions. The data were run for a cavity having Kanthal on the cavity side walls with a .582 inch gap and four $\frac{1}{32}$ inch slots per drift tube and spaced $\frac{5}{8}$ inch apart. Curve A is for no R.F. loading on drift tubes and Curve B for R.F. loading on drift tubes. It should be noted that although axially parallel slots are preferred non-axially parallel cases although less effective are included in the teachings as mere deviations of the general preferred case.

In summation then, it is seen that the utilization of the slotted drift tube approach of the present invention results in reducing the resonant frequency for the TE_{111} type mode without substantial perturbation of the operating mode. It is thought that, regardless of whether or not lossy R.F. material is applied to the slotted region of the drift tubes that the use of slots which reduce the resonant frequency of TE_{111} type modes at least 10% or more with respect to the nonslotted resonant frequency of the TE_{111} type mode should be very useful and if the cavity walls are coated with R.F. lossy material substantial decreases in the Q_o of TE_{111} type modes occurs due to the perturbation of the mode which produces increased cavity wall currents. However, the combination of slots and R.F. lossy material in the slotted region has been shown to be most effective.

Since many changes could be made in the above construction and many apparently widely different embodiments could be constructed without departing from the scope thereof it is intended that all matter contained in the above description or shown in the accompanying drawings shall be interpreted as illustrative and not in a limiting sense.

What is claimed is:

1. A high frequency electron discharge device including beam forming and projecting means disposed at an upstream end portion of said device for generating and directing an electron beam along the central beam axis of the device, a plurality of cavity resonators disposed along the beam axis, said cavity resonators having re-entrant drift tube portions disposed about the central beam axis for permitting the electron beam to pass from cavity resonator to cavity resonator along said central beam axis, at least some of said re-entrant drift tubes being provided with elongated slotted regions which introduce a plurality of substantially axially directed and circumferentially spaced current flow paths in the re-entrant portion of said drift tubes, said slotted regions introducing at least a 10% or more reduction in the resonant frequency of the TE_{111} type cavity mode in the respective cavity resonators in which they are utilized with respect to the resonant frequency of the same TE_{111} type cavity mode in the absence of said slotted regions and wherein said drift tubes are provided with lossy R.F. attenuating material in said slotted regions.

2. A high frequency electron discharge device operable in the microwave spectrum comprising electron beam forming and projecting means disposed at an upstream end portion of the device for producing and directing an electron beam along an elongated central beam axis, electron collector means disposed at the downstream end portion of the device for absorbing the spent beam and beam-wave interaction means disposed along the device axis between said upstream and downstream end portions, said beam-wave interaction means including at least one cavity resonator having a re-entrant drift tube portion disposed within a cavity end wall about said beam axis, said re-entrant drift tube being characterized by having a plurality of elongated slots forming a plurality of fingers in the re-entrant portion thereof which extend from the free end towards said cavity end wall beyond

said free end, said plurality of fingers being provided with lossy R.F. attenuating material.

3. The device defined in claim 2 wherein said lossy R.F. attenuating material is disposed on the internal surface of said drift tube.

4. The device defined in claim 2 wherein said lossy R.F. attenuating material is disposed on the external surface of said drift tube.

5. The device defined in claim 2 wherein said lossy R.F. attenuating material is disposed on both the internal and external surfaces of said drift tube.

6. The device defined in claim 2 wherein said cavity resonator includes a pair of re-entrant drift tubes disposed about said beam axis in axial alignment from the respective cavity end walls and wherein said slots are axially parallel to and radial with respect to said beam axis. 15

7. The device defined in claim 2 wherein said cavity resonator includes a pair of re-entrant drift tubes disposed

about said beam axis in axial alignment from the respective cavity end walls and wherein said slots are axially parallel to and nonradial with respect to said beam axis.

8. The device in claim 7 wherein the individual slots in opposing drift tubes are azimuthally out of phase with respect to each other.
